UNITED STATES PATENT OFFICE.

ORIS K. DUNBAR, OF CENTERVILLE, INDIANA.

ANCHOR-DRILL.

1,147,791.

Specification of Letters Patent. Patented July 27, 1915.

Application filed January 21, 1914. Serial No. 813,396.

To all whom it may concern:

Be it known that I, ORIS K. DUNBAR, a citizen of the United States, residing at Centerville, in the county of Wayne and

5 State of Indiana, have invented a new and useful Anchor-Drill, of which the following is a specification.

It is the object of my invention to provide a simple, strong, and inexpensive ground 10 anchor, for use, for instance, in anchoring wire fences, tents, or other things to the ground, and a simple and effective drill for making a hole for the reception of this anchor, the anchor being inserted into its 15 hole through part of the drill.

The accompanying drawing illustrates my invention.

Figure 1 is an elevation of the anchor drill; Fig. 2 is a longitudinal section through 20 the anchor drill; Fig. 3 is a longitudinal section through the tubular member of the anchor drill when in the ground, showing the anchor being inserted; Fig. 4 is a sectional view showing the anchor in anchoring 25 position in the ground, the drill being entirely removed; and Fig. 5 is a transverse section on the line 5—5 of Fig. 3.

The anchor drill comprises an outer tubular-member 10, conveniently made of gas 30 pipe, and an inner member 11 which is slideable freely within the tubular member 10 and is conveniently an ordinary iron or steel rod. The inner member 11 is provided at its upper end with a weight 13, having a 35 handle 14, the member 11 conveniently being screw-threaded into the lower end of the weight. This lower end of the weight is conveniently counter-bored so that it can fit loosely over a pipe coupling 15 screw-threaded on the upper end of the tubular member 10, such coupling projecting slightly beyond the upper end of the member 10 proper, so that the blows from the weight 13 will come upon such coupling and not on the end 40 of the pipe 10; this permits the coupling 15, when battered, to be replaced at the cost of a few cents, without necessitating the replacement of the whole pipe 10. If desired, a lead cushion 16 may be placed in the 45 counter-bored lower end of the weight 13, for lessening the battering of the coupling 15. The tubular member 10 is conveniently provided near its upper end with a handle 17. The lower ends of both members 10 and 11 50 are preferably tapered, and the member 11 is sufficiently longer than is the member 10

so that when the weight 13 rests against the coupling 15 the lower pointed end 18 of the rod 11 projects slightly below the lower end of the tubular member 10.

60

In operation, the member 10 is set at the place on the ground where a hole is desired, and the member 11 is reciprocated up and down in the member 10. On each down

stroke of the member 11 the weight 13 strikes the coupling 15 and the pointed end of the member 11 strikes the ground, thus forcing both members 10 and 11 down into the ground.

This is done with comparative ease even in the hardest earth and in soft rocks, 70 making a clean hole. When the hole has been made to the desired depth, the inner member 11 is withdrawn, leaving the tubular member 10 in place.

Then an anchor, which consists of a member 20 which is a section of 75 a tube so that in cross section it is an arch of preferably less than 180° and which is longer than the diameter of the tubular member 10 and is pointed at one end 21 at the crown and at the other end 21' at the

80 bases of the cross sectional arch and is provided with holes 22 nearer the end 21', and is mounted in the bight of a looped wire 23 passing through the holes 22, is dropped

lengthwise through the tubular member 10 85 by means of such wire, which is bent to lie in the groove formed by the concave side of the anchor 20, the anchor and the looped wire together being smaller in diameter than

90 is the inside of the tube 10, as shown in Fig. 3. When the anchor 21 has been dropped to the bottom of the hole formed in the ground, the tubular member 10 is pulled up, leaving the anchor 20 and wire 23 in the hole,

95 and after such member has been gotten out of the way an upward pull is given on the wire 23. This causes the point 21 to dig into one side of the hole in the ground, and the point 21' to cut upward into the other side of such

hole, so that the continued upward pull 100 on the wire 23 eventually brings the member 20 crosswise of the hole, as shown in Fig. 4.

When in this position, the anchor will stand a very considerable strain without pulling out. The shorter end of the anchor 20 is 105 prevented from being pulled too far upward, not only by the pressure of the ground above it, but by the bend which was formed on the

wire 23 when such wire was bent to make it lie within the anchor 20 as such anchor was 110 being dropped through the tubular member 10.

I claim as my invention:

1. An earth drill, comprising a tubular member, a member reciprocable longitudinally within said tubular member, said reciprocable member having rigid with it at one end a weight which overhangs the tubular member so that by the reciprocations of said reciprocable member the weight may be made repeatedly to engage the end of said tubular member, said reciprocatory member being sufficiently long so that when said weight engages one end of said tubular member the reciprocatory member projects slightly beyond the other end of said tubular member.
2. An earth drill, comprising a tubular member, a member reciprocable longitudinally within said tubular member, said reciprocable member having rigid with it at one end a weight which overhangs the tubular member so that by the reciprocations of said reciprocable member the weight may be made repeatedly to engage the end of said tubular member.
3. An earth drill, comprising a tubular member, a member reciprocable longitudinally within said tubular member, said reciprocable member having rigid with it at one end a weight which overhangs the tubular member so that by the reciprocations of said reciprocable member the weight may be made repeatedly to engage the end of said tubular member, the end of the tubular member which is engaged by said weight being provided with a removable part which takes the blows from the weight.
4. An earth drill, comprising a tubular member, a member reciprocable longitudinally within said tubular member, said reciprocable member having rigid with it at one end a weight which overhangs the tubular member so that by the reciprocations of said reciprocable member the weight may be made repeatedly to engage the end of said tubular member, said weight where it engages said tubular member being provided with a cushion of soft metal for reducing battering.
5. An earth drill, comprising a tubular member, a member reciprocable longitudinally within said tubular member, said re-

ciprocable member having rigid with it at one end a weight which overhangs the tubular member so that by the reciprocations of said reciprocable member the weight may be made repeatedly to engage the end of said tubular member, said weight and said tubular member near the end engaged by said weight each being provided with a handle.

6. A hand-operated earth drill, comprising a tubular member provided with means whereby it may be grasped by the hand of the operator, and a member reciprocable longitudinally within said tubular member, said reciprocable member having rigid with it at one end a weight which overhangs the tubular member so that by the reciprocations of said reciprocable member the weight may be made repeatedly to engage the end of said tubular member and also having means whereby it may be separately grasped by the operator so that it may be reciprocated within said tubular member, said reciprocatory member being sufficiently long so that when said weight engages one end of said tubular member the reciprocatory member projects slightly beyond the other end of said tubular member.

7. A hand-operated earth drill, comprising a tubular member provided with means whereby it may be grasped by the hand of the operator, and a member reciprocable longitudinally within said tubular member, said reciprocable member having rigid with it at one end a weight which overhangs the tubular member so that by the reciprocations of said reciprocable member the weight may be made repeatedly to engage the end of said tubular member and also having means whereby it may be separately grasped by the operator so that it may be reciprocated within said tubular member.

In witness whereof, I, have hereunto set my hand at Indianapolis, Indiana, this nineteenth day of January, A. D. one thousand nine hundred and fourteen.

ORIS K. DUNBAR.
